UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

SUPPORT-ARM BRACKET.

Application filed May 6, 1927. Serial No. 189,235.

My invention relates to railway rolling stock and consists in an improved mounting for a brake beam support or guide arm.

The object of my invention is to provide 5 an inexpensive, simple, and effective bracket by which the guide arm or support may be secured to a truck part, such as the spring plank.

In the accompanying drawings which illustrate a selected embodiment of my invention—

Figure 1 is a longitudinal section through a portion of a truck structure illustrating the spring plank, my improved bracket, the 15 support or guide arm carried thereby, and the adjacent brake beam, head, shoe, and wheel tread.

Figure 2 is a vertical transverse section taken on line 2—2 of Figure 1.

20 Figure 3 is a view of the plate from which my improved bracket is formed.

Figure 4 is an isometric view of the improved bracket after it is completed.

In the drawings, the truck spring plank 25 is indicated at 1, an adjacent wheel at 2, and a truss brake beam is also indicated, the compression member of the beam being shown at 3, the tension member at 4, the strut at 5, and the brake head at 6. It will be 30 understood that the beam is supported by the usual hangers 7. It is customary to provide a support for the beam which will function in the event that the hangers break. Such a support is indicated by the angle iron 35 8 which is carried on the spring plank by means of my improved bracket which comprises a U-shaped body 9, the legs of which are flanged outwardly as indicated at 10 and bear against the lower face of the spring 40 plank 1. The ends of each flange 10 are turned upwardly to form the ears 11 which engage the vertically extending flanges on the spring plank and may be secured thereto by rivets 12 or otherwise. Preferably 45 the support 8 is yieldingly carried in bracket 9 by means of a flat spring 13 which is seated between upturned lips 14 on the bottom of the bracket and is locked in position by a suitable pin 15 which also engages 50 a recess in the vertical leg of the angle iron to prevent longitudinal movement of the latter.

Preferably the bracket is formed from a single plate as illustrated in Figure 3; the 55 U-shaped body of the bracket being formed

by bending the plate on the lines *x*; the flanges on the legs of the body being formed by bending the plate on the lines *y*; and the upturned ears on the ends of the flanges being formed by bending the plates on the 60 lines *z*. However, this particular formation of the bracket is not essential and the same may take the form of a casting or of two or more parts welded or riveted to each other.

65 In any form of my invention the bracket is secured to the flanges of the spring plank channel which is more desirable than riveting it to the web of the channel, and the bracket is supported at points spaced transversely of its body and outside of the support or guide arm, thereby rendering the support more stable than if the securing means were positioned immediately above the longitudinal center line of the bracket 70 as has been previously suggested.

I contemplate the exclusive use of such modifications in the details of my invention as fall within the scope of my claims.

I claim:

1. In combination, a horizontally disposed car truck part having a vertical surface, a U-shaped bracket below and extending transversely of said truck part, a brake beam guide or support arm positioned in said support bracket and extending beyond the ends of the same, elements on said bracket at each side of said arm and secured to said vertical surface on said truck part, and a yielding element extending substantially 90 throughout the length of said bracket, carried on the bottom thereof and supporting said arm.

2. In a one-piece bracket for mounting a brake beam guide or support arm, a U-shaped section forming a seat for said arm, outturned flanges on the legs of said section, and upturned rigid ears on the ends of said flanges by which the bracket may be secured to a car part, said section forming an inclosure extending lengthwise of the bracket, to receive a yielding element disposed longitudinally of the section, and adapted to support said arm, and also adapted to receive an element for retaining said arm against 100 movement longitudinally of the bracket.

3. In combination, a horizontally disposed car truck part having a vertical surface extending transversely of the truck, a U-shaped bracket extending longitudinally of the 110

- truck below said truck part, an angle iron forming a brake beam guide or support arm extending through said bracket with one leg disposed vertically at one side of said bracket and the other leg disposed horizontally at the top of said bracket, and a leaf spring carried on the bottom wall of said bracket and extending lengthwise of the latter and engaging the under side of the horizontal leg of said angle iron at points adjacent to the sides of said truck part.
4. In combination, a horizontally disposed car truck part having a vertical surface extending transversely of the truck, a U-shaped bracket extending longitudinally of the truck below said truck part, an angle iron forming a brake beam guide or support arm extending through said bracket with one leg disposed vertically at one side of said bracket and the other leg disposed horizontally at the top of said bracket, a leaf spring carried on the bottom wall of said bracket and extending lengthwise of the latter and engaging the inner side of the horizontal leg of said angle iron at points adjacent to the sides of said truck part, and a transverse pin extending through the sides of said bracket and a depression in said spring and a recess in said arm for retaining said spring and arm in said bracket and integral lugs on said bracket adapted to be bent to position the ends of said spring.
5. In combination, a horizontally disposed car truck part having a vertical surface extending transversely of the truck, a U-shaped bracket extending longitudinally of the truck below said truck part, an angle iron forming a brake beam guide or support arm extending through said bracket with one leg disposed vertically at one side of said bracket and the other leg disposed horizontally at the top of said bracket, a leaf spring carried on the bottom wall of said bracket and extending lengthwise of the latter and engaging the inner side of the horizontal leg of said angle iron at points adjacent to the sides of said truck part, and a transverse pin extending through the sides of said bracket and a depression in said spring and a recess in said arm for retaining said spring and arm in said bracket and integral lugs on said bracket adapted to be bent to position the ends of said spring.

In testimony whereof, I hereunto affix my signature this 22nd day of April, 1927.

EDWIN G. BUSSE.
